(57) **CLAIM**

The ornamental design for an escutcheon, as shown and described.

DESCRIPTION

FIG. 1 is a perspective view of an escutcheon of the new design;

FIG. 2 is a front elevational view of the escutcheon of FIG. 1; FIG. 3 is a left side elevational view of the escutcheon of FIG. 1, the right side elevational view being a mirror image thereof; and,

FIG. 4 is a top plan view of the escutcheon of FIG. 1, the bottom plan view being a mirror image thereof.

The broken line showing of unclaimed portions of the escutcheon forms no part of the claimed design.
